UNITED STATES PATENT OFFICE

2,565,714

ROWING DEVICE

Gene W. Anderson, Gig Harbor, Wash.

Application February 11, 1947, Serial No. 727,755

1 Claim. (Cl. 9—25)

1

This invention relates to oars and it has reference more particularly to improvements in oars of that kind referred to as "forward rowing" oars; it being the principal object of the invention to provide a novel oar structure, designed for either forward or backward rowing and readily convertible from one type to the other.

It is also an object of the invention to provide an oar structure, for both forward and backward rowing, and which permits the necessary up and down angular movement of the oar for dipping the blade into and lifting it from the water in either of the manners of use of the oar.

Another object of the invention is to provide an oar of the above kind that is of simplified yet durable construction and especially desirable for pleasure craft.

Other objects of the invention reside in the details of construction of parts, in their combination and mode of use, as will hereinafter be fully described.

In accomplishing the above listed and other objects of the invention, I have provided the improved details of construction, the preferred forms of which are illustrated in the accompanying drawings wherein:

Fig. 1 is a plan view of a boat that is equipped with oars embodying the improvements of the present invention therein.

Fig. 2 is an enlarged, plan view of a portion of one of the oars particularly illustrating the geared connection between the handle and blade portions of the oar.

Fig. 3 is a side view of the parts as shown in Fig. 2.

Fig. 4 is a cross-section, taken on the line 4—4 in Fig. 2.

Fig. 5 is a longitudinal, sectional detail showing the gear locking means used in converting the oar from forward to backward rowing.

Referring more in detail to the drawings—

The present oar is intended for use as in normal boat rowing operations and is applied to the boat in the usual position and is handled in the same manner as the usual type of oar is handled.

In its present preferred form of construction, the oar comprises an inner end portion, or what I call the handle portion, 10, and an outer end portion herein called the blade portion, 12. Together these portions, as herein assembled, make up an oar of normal length.

The handle portion 10 is equipped at its outer end with a gear segment 14 and the blade portion 12, likewise, is equipped at its inner end with a gear segment 15. The two gear segments are sup-

2

ported in operative mesh as presently explained and are rotatably mounted for turning on their mounting axis.

The means for mounting the gear segments to which the blade and handle portions of the oar are applied, comprises a frame made up of a base plate 16 and a top plate 17. These two plates are disposed in parallel vertically spaced planes and are rigidly joined in this relationship by bolts 18 that extend through the plates. Tubular spacers 19 are applied about the bolts between the plates, as best shown in Fig. 5, and these spacers and bolts hold the plates in a definite, spaced relationship.

15 The gear segments, 14 and 15, are mounted between the plates and rotate, respectively, on the spacer tubes 19—19 which serve as mounting axes for the said segments.

The base plate 16 is equipped at opposite edges 20 midway between the pivot bolts, with spaced down turned ears 20—20 and the frame structure, comprised by the plates 16 and 17, is operatively supported by an oar lock comprising a vertical pivot pin or shank 21 having a head portion 22 at its upper end; the head portion being disposed between the ears 20—20 and pivotally secured thereto by a horizontal pivot pin 23 extended therethrough as best shown in Fig. 4. The shank 21 is adapted to be mounted in a vertical socket 25 that is formed at the outer end of a plate 26 that is fixed rigidly to the rail 27 of the boat 28 as shown in Figs. 1 and 3. This socket, however, might be in the rail itself if the width of the boat is such that this can be done without convenience 30 to the oarsman.

35 It should be explained here that for forward rowing, the shank 21 is locked against turning in its socket. This is effected by extending a pin 29 diametrically through the socket member and shank as shown in Fig. 3, the parts being drilled for the reception of this locking pin.

In the arrangement as seen in Figs. 2 and 3 which is that for forward rowing, it is to be noted that the line of the axes of the gear segments 45 is transversely of the boat and that the pivot pin 23 is horizontally disposed and extends in the longitudinal direction of the boat. Thus while the oar may be dipped up and down by the pivoting of the frame about the axis of the pin 23, the pivot axes about which the gear segments are mounted maintain their alignment 50 in a transverse vertical plane.

Assuming the parts to be so constructed and assembled, and considering the shank 21 to be 55 held against rotation in the socket, it is to be

understood that the frame may pivot on pin 23 and the oar may be dipped into or lifted from the water in the usual way by raising and lowering the handle portion. With the oarsman facing the forward end of the boat and the oar handles extended to normal handling position forwardly of him, rearward pull on the handle portions will, by reason of use of the pivotally mounted and intermeshing geared segments 14 and 15, cause the blade portions of the oars to be swung rearwardly, and thus the boat may be driven forwardly. Likewise, when the handle portions are returned forwardly, the blade portions move forwardly.

If it is desired to use the oars for backward rowing after the fashion of use of the usual type of oar, the locking pins 29 are withdrawn so that the shanks 21 may then rotate freely in their sockets. Then the handle and blade portions of the oars are brought into alignment and the gear segments of each are locked against relative turning. This locking of the gear segments is effected by means best shown in Fig. 5 wherein it is noted that each gear segment is formed with an opening 30 therethrough and that a latch plate 31 is mounted on the top plate 17 and has downturned opposite end portions 32-32 designed to pass through openings 34 in the plate 17 and to engage in the openings 30-30 of the gear segments so that they will be held locked relative to each other.

The latch plate 31 is mounted by a leaf spring member 35 attached at one end to plate 17 and this yieldingly holds the latch set but permits it to be manually raised and its end portions disengaged from the gear openings when it is desired to convert the oar for forward rowing purposes. When the gear segments are locked against turning and the shank 21 is free to rotate, the oar structure may be pivoted up and down on the bolt 23 and swung forward and rearward about the supporting shank in the manner of the ordinary oar.

Oars of this kind are especially desirable for resort boats where used primarily for pleasure purposes, but are useful and sometimes very desirable for ordinary boat rowing operations.

Changes in size and proportion of parts may be made and various materials may be employed

in their construction without departing from the spirit of the invention and therefore it is not desired that the claim shall be limited in this respect but that they shall be given an interpretation that is commensurate with the scope of the invention disclosed herein.

Having thus described my invention, what I claim as new therein and desire to secure by Letters-Patent is:

- 10 The combination with a boat having an oar lock socket, of an oar structure adapted for forward or backward rowing comprising an oar lock having a vertical mounting stem mounted for axial rotation in said socket, a frame mounted 15 hingedly upon said oar lock for oscillation about a horizontal axis that extends in a direction generally lengthwise of the boat, said frame comprising substantially horizontally disposed and vertically spaced, rigidly joined plates, gear segments mounted pivotally between the plates in 20 intermeshed relationship, each formed with an upwardly opening socket, an oar handle fixed to one segment and extended inboard, an oar blade fixed to the other segment and extended outboard, said upper frame plate having holes therethrough with which the sockets in the gear segments may be registered, a locking pin removably applied through the socket and stem to 25 secure the oar lock against turning for forward rowing, and a locking means mounted on the upper frame plate including a plate having legs adapted to extend through the plate openings to engage within the gear sockets to hold the gear segments against relative turning, and yieldable means for retaining the locking means in 30 locked position.
